UNITED STATES PATENT OFFICE

164,107

BASKET HAND BROILER

Joseph W. Doblin, New York, N. Y.

Application January 6, 1949, Serial No. 86

Term of patent 14 years

(Cl. D44—1)

To all whom it may concern:

Be it known that I, Joseph W. Doblin, a citizen of the United States and a resident of New York, in the county of New York and State of New York, have invented a new, original, and ornamental Design for Basket Hand Broiler, of which the following is a specification, reference being had to the accompanying drawing forming part thereof, in which:

Fig. 1 is a perspective view of a basket hand broiler showing my new design; and

Fig. 2 is a perspective view of the basket hand broiler in its open position.

I claim:

The ornamental design for a basket hand broiler, as shown.

JOSEPH W. DOBLIN.
